UNITED STATES PATENT OFFICE.

WALTER A. HALL, OF LYNN, MASSACHUSETTS, ASSIGNOR TO GENERAL ELECTRIC COMPANY, A CORPORATION OF NEW YORK.

DESIGN FOR A TRANSFORMER-CASE.

No. 38,698.

Specification for Design.

Patented July 28, 1907.

Application filed October 3, 1904. Serial No. 227,063. Term of patent 14 years.

To all whom it may concern:

Be it known that I, WALTER A. HALL, a citizen of the United States, residing at Lynn, in the county of Essex and State of Massachusetts, have invented a new, original, and ornamental Design for Transformer-Cases, of which the following is a specification, reference being had to the accompanying drawing, forming a part hereof, in which

Figure 1 is a perspective view of a trans-

former casing showing my new design; Fig. 2 is a side elevation; and Fig. 3 is an inverted plan-view.

I claim,

The ornamental design for a transformer case as shown.

WALTER A. HALL.
